(57) **CLAIM**

The ornamental design of a switch, as shown and described.

DESCRIPTION

FIG. 1 is a front view of a switch in accordance with the present invention;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken line showing in the figure drawings is included for illustrative purposes only and forms no part of the claimed design.
